UNITED STATES PATENT OFFICE.

ALBERT ALFRED MEAD, OF LEE, ENGLAND, ASSIGNOR TO J. STONE & COMPANY
LIMITED, OF DEPTFORD, ENGLAND.

VENTILATING MEANS FOR RAILWAY AND OTHER VEHICLES.

1,098,329.

Specification of Letters Patent.

Patented May 26, 1914.

Application filed December 30, 1912. Serial No. 739,321.

To all whom it may concern:

Be it known that I, ALBERT ALFRED MEAD, a subject of the King of Great Britain, and resident of "Aldersyde," No. 12 Lansdown road, Lee, in the county of Kent, England, have invented new and useful Improvements in Ventilating Means for Railway and other Vehicles, of which the following is a specification.

10 This invention relates to improvements in ventilating means for railway and other vehicles or carriages, and concerns that class of ventilating appliance which comprises a set of vertical swiveling strips, which may 15 be of glass, metal, wood or other suitable material, and which are adapted to be simultaneously and similarly turned about their vertical pivots in one direction or the other, according to the direction of travel, for the 20 purpose of obtaining a louver-like ventilator which can be suited for travel in either direction. These ventilators are not by themselves adapted to effectually prevent draft when closed, and when open they may 25 in certain positions admit cinders, rain and solid particles emitted by the locomotive or caught up by the passage of the vehicle through the air.

30 The object of the present invention is to remove these defects and to enable a ventilator of the louver type to be used as effectively as heretofore, but with additional comfort to the passengers.

According to this invention a "hit and 35 miss" grating is combined with a louver ventilator, a slide of the grating being movable to open or close vertical slots simultaneously with the swiveling of the strips to open and close the louver.

40 The invention will be fully described with reference to the example of construction shown in the accompanying drawings in which:—

Figure 1 is a rear elevation partly in 45 section of a ventilator, sufficient of which is shown for the purpose of this specification. Fig. 2 is a section on the line II—II, Fig. 1, looking in the direction of the arrow. Fig. 3 is a combined plan and horizontal section of Fig. 1. Fig. 4 is a view similar to Fig. 3 showing the ventilator open, and Fig. 5 is a vertical section on the line V—V, Fig. 2. Fig. 6 is partly a plan and partly a horizontal section on the 50 line VI—VI of Fig. 7 which is a vertical

section on the line VII—VII Fig. 6 of a modification. Fig. 8 is a section, similar to Fig. 2, of the lower part of a ventilator having modified means for operating the louvers. Fig. 9 is a section view similar to Fig. 2 but illustrating other modified means for operating the louvers, and Fig. 10 is a section, similar to Fig. 2 of the upper part of a ventilator having further modified means for operating the louvers. 60

The ventilator is supported in a suitable casing or frame, which in the construction shown comprises an upper horizontal member 1 and a lower horizontal member 2, distanced apart by vertical rods or stays 3, 70 and by vertical end frame members, which latter, however, are not illustrated.

The "hit and miss" grating comprises a slide 4 formed with vertical slots 5, which upon movement of said slide 4 are adapted 75 to be brought opposite vertical slots 6 in a stationary plate 7 fixed within the frame, said slide 4 being so constructed as to be capable of movement in both a right hand and a left hand direction, from its closed 80 position, in order to open the slots 6 in the stationary plate 7.

8 are the strips which form the louver and they have at their lower ends shoes 9 provided with pivot pins 10, which latter 85 may be of a spherical nature, or be stepped on balls 11 located in recesses in the lower frame member 2, by means of which freedom of movement of the said strips 8 is insured.

Caps 12 are in a known manner provided at the upper ends of the strips 8, each cap 12 having an upwardly projecting pin 13. These pins 13 engage semicircular recesses 90 formed in the forward face of the upper frame member 1, and are retained therein by plates 14 having corresponding semi-cylindrical recesses which together with the recesses in the frame member 1 constitute 95 bearings for the pivot pins 13. Lateral bifurcated lugs 15 on the caps 12 are adapted to be engaged by depending pins 16 on a horizontal bar 17 which latter rests upon the lugs 15, and by means of which bar 17 the strips 8 are simultaneously and similarly 100 turned on their pivots.

The vertical slots 6 in the stationary plate 7 are preferably arranged immediately opposite or in front of the pivots of the louver strips 8, as seen best in Fig. 4, or they may 110

be to one side or the other of the position shown. When, therefore, the slide 4 is moved to open the slots 6, and to simultaneously turn the strips 8 on their pivots, to 5 open the louver as hereinafter described, should cinders or other solid particles pass through the louver, they will be deflected on to solid parts 5^a and 6^a between the slots 5 and 6 in the slide 4 and plate 7, and being 10 arrested thereby will fall to the bottom of the ventilator. The frame or casing of the ventilator may be provided with means such as the outlet 18, shown in chain lines in Fig. 2, whereby the said solid particles after falling 15 to the bottom of the ventilator may be delivered to the exterior of the carriage or vehicle being ventilated.

A plate 19 is shown attached to the rear of the slide 4 and extending across one of 20 the vertical slots 5 therein (see Fig. 5). To this plate 19 is fixed a forwardly extending stud or pin 20 having at its outer end a knob or handle 21, the said pin 20 passing through a horizontal slot 22 formed in the stationary 25 plate 7. When the ventilator is closed, that is when the slots 6 in the plate 7 are closed, and the louver strips 8 are in alinement in the closed position, as shown in Fig. 3, the pin 20 is in the center of the slot 22, thus by 30 moving the knob 21 in either a right hand or a left hand direction the slots 6 are opened by the slots 5 in the slide 4 registering therewith. In order that the movements of the slide 4 shall simultaneously impart 35 swiveling movement to the strips 8 the plate 19 is provided for example with an upwardly projecting arm 23 having at its upper end a forked lateral extension 24. Engaging the fork of the extension 24 is a pin 40 25 on one of the lugs 15 as seen clearly in Figs. 2, 4 and 5, so that when the slide 4 is moved in either direction it turns the louver strip 8 which carries the pin 25 through the medium of the arm 23, and as all the strips 45 8 are operatively connected by the horizontal bar 17 as aforesaid, they are caused to simultaneously swivel on their pivots. Another mode of turning the strips 8 is illustrated in Fig. 8 and consists in providing the 50 plate 19 with a downwardly projecting arm 41 having a forked lateral extension 42 for engaging, say a pin 43, carried by a lug 44 on the shoe 9 of one of the louvers. Or as shown in Fig. 9, said plate 19 may have both 55 upwardly and downwardly extending arms 23 and 41, respectively, for engaging corresponding lugs 15 and 44 on the cap 12 and shoe 9 in the manner aforesaid.

Instead of providing the arm or arms on 60 the plate 19, the connection between the slide 4 and the louver strips 8, as shown in Fig. 10, may for instance be made by a pin 45, say on the rear of the slide 4 engaging a recess 46 or the like in the horizontal bar 17 65 so that upon moving the slide 4 the bar 17

would be moved in the same direction and, through the pins 16 thereon engaging the lugs 15, effect the simultaneous partial rotation of the said strips.

To enable the ventilator to be operated 70 from outside the carriage a forwardly projecting arm 26 may be attached to a vertical pin 27 in the horizontal bar 17. The said pin passes upward through a slot 28 in the upper member 1 of the frame, a knob or 75 handle which is accessible from the exterior of the carriage being fitted to the outer end of the said arm 26, by means of which the bar can be moved in either a right hand or left hand direction, and through the connections before described, effect the sliding of 80 the slide 4, and at the same time the swiveling of the strips 8, as will be well understood.

To enable the device to be operated with 85 ease, and to avoid excessive wear and tear and difficulties of operation which arise when cinders and similar bodies clog the working parts of the ventilator, the slide 4 may be supported on balls 29 (Fig. 2), and 90 the horizontal bar 17 be provided with a ball 30, see Fig. 1, or roller or similar anti-friction bearing, at each end of the said bar, and intermediately also if desired, which balls or the like bear against the 95 frame member 1.

To indicate when the ventilator is closed, or to hold the same in the closed position, a spring ball-catch 47 of the well-known type, or any other snap or suitable catch 100 device may, as shown in Figs. 1 and 2, be adapted to co-act between the slide 4 and the stationary plate 7, and so arranged as to operate or snap when the slide 4 is in its mid-position, as illustrated in Fig. 1, in 105 which position, as before stated, both the vertical slots 5 in the slide 4, and the louver are closed. Obviously any other suitable engaging device or indicator may be employed for this purpose.

In the modification seen in Figs. 6 and 7 the top member 1, the bottom member 2, the side members 31, and the fixed plate 7 of the hit-and-miss grating, are all made of sheet metal and, if desired, they may be 115 formed of one piece of sheet metal, so that a sort of sheet-metal box or casing is provided, the open front of which is capable of being closed by the louver plates 8. These plates 8 may also be made of sheet metal and 120 may be stiffened by pivot pins 32 which may extend from top to bottom of such louver plates 8, the said pins being, if desired, soldered to the plates 8. It is convenient in cutting out or stamping the louver plates 8 to form the same with lugs 33, 34 which are bent at right angles to the planes of respective plates so that the pins may pass through and be secured in, such lugs. The lugs 33 125 are conveniently extended so as to form the 13

forked arms 15 which engage pins or projections on a sliding member by which the louver plates 8 are turned about their pivots simultaneously with the sliding of the plate 5 of the hit-and-miss grating. In this modification the sliding bar 17 of the construction described with reference to Figs. 1 to 5 is dispensed with and each louver plate is turned by a respective pin or projection 35 riveted or otherwise secured to the sliding plate 4 of the hit-and-miss slide. Such pins 35 may be made by suitably bending short lengths of wire, as shown, and flattening those ends which are secured to the sliding plate 4. In order to prevent the plate 4 from bending so that it will maintain a close relation with the fixed plate 7, anti-friction rollers 36 may be mounted upon vertical studs on the top and bottom plates 1 and 2 respectively so as to bear against the plate 4 at various points and preserve the straightness of the plate 4, and its close relation with the fixed plate 7. In order to prevent the louver plates 8 from rattling and displacement due to vibration, spring washers 37, or other resilient devices, may be inserted between the top plate 1 and collars on the pins 32, or the lugs 33 may serve as collars for receiving the pressure of the springs 37 as shown. Similar washers may be introduced between the lugs 34 and the bottom plate 2, or such spring washers or resilient devices may be applied at both the top and bottom of each pivot pin 32. An advantage incidental to the use of devices such as spring washers is that the latter cause the louver plates to turn sufficiently stiffly about their pivots so that the possibility of such plates being turned unintentionally by the vibration and jolting is removed and the ventilator remains in any position to which it has been adjusted by the handle 21, which latter moves in a plain slot as in the previous construction. The bottom plate 2 is slotted to allow cinders and other matter to fall through so that they cannot clog the ventilator, such bodies may fall through on to a downwardly and outwardly inclined floor 38 by which they are delivered to the exterior of the carriage. The vertical corner spaces of the casing may be filled in by means of bent sheet metal pieces 39 which prevent lodgment of cinders and other matter in such corners. It may be observed that in this construction the pivots 32 are situated midway between neighboring and corresponding slots 6 in the fixed plate 7 and that the number of louver plates 8 is one in excess of the slots 6. It may also be pointed out that the sliding plate 4 is formed with eight slots 5 four of which are shown in register with the four slots 6 while the other four are situated behind imperforate parts of the plate 7. If the handle 21 be moved to the opposite ex-

treme position to reverse the louver plates 8 the slots 5 shown not in register, will be brought into registration with the slots 6, while those shown in register will be moved toward the right hand of Fig. 6, behind imperforate parts of the plate 7. This arrangement is very suitable for the interception of cinders or bodies which may be deflected into the casing by the louver plates 8.

The bottom plate 2 may be stiffened by a bar 40 secured along the edge of such plate and such stiffeners may be employed at any places where they may be required.

I claim:

1. Ventilating means for railway carriages and other vehicles, comprising a chamber, a "hit and miss" grating including a slide at the rear of said chamber, a series of louvers pivotally mounted in the entrance of said chamber in front of said slide, and operative connection between said slide and said louvers whereby the movement of said slide to open or close the slots in the grating brings about simultaneously the movement of the louver strips so that the latter open or close the entrance to said chamber.

2. Ventilating means, comprising a chamber, a "hit and miss" grating at the rear of said chamber and having movable and stationary members with slots therein, a series of louver strips mounted in the entrance of said chamber in front of said grating, vertical pivots for said louver strips located approximately opposite the slots in said stationary member, and operative connection between said movable member and said louver strips substantially for the purpose set forth.

3. Ventilating means, comprising a chamber, a "hit and miss" grating including a slide at the rear of said chamber, swiveling louver strips pivotally mounted in the entrance of said chamber and adapted to close or open said entrance, a horizontal sliding bar operatively connecting said louver strips, and operative connection between said slide and said bar comprising an arm on the slide, and a lug on one of the louver strips adapted to be operatively engaged by said arm, whereby the movement of said slide causes the louver strips to be simultaneously swiveled, substantially as set forth.

4. Ventilating means, comprising a chamber, a "hit and miss" grating including a slide at the rear of said chamber, swiveling louvers mounted in the entrance of said chamber in front of said slide, crank arms on said louvers, and pins or projections carried by the slide and operatively engaging said crank arms, substantially as and for the purpose set forth.

5. Ventilating means, comprising a chamber, a "hit and miss" grating including a

slide at the rear of said chamber, a series of louvers mounted in the entrance of said chamber in front of said slide and adapted to open or close said entrance, operative connection between the slide and louvers, vertical pivots for said louvers, and elastic means on the pivots of the louver plates, substantially as and for the purpose set forth.

10 6. Ventilating means, comprising a chamber, a "hit and miss" grating including a fixed plate and a slide at the rear of said chamber, a series of louvers mounted in the entrance of said chamber in front of said

15 grating and adapted to open or close said entrance, operative connection between the slide and louvers, vertical pivots for said louvers, and antifriction rollers to maintain the slide in close relation with the fixed 20 plate of the grating, substantially as set forth.

7. Ventilating means, comprising an open 25 sided casing having ports in one wall, a slotted plate slidably arranged in relation with said wall, a series of louver strips pivotally mounted at the open side of said casing, and adapted to open or close such open side, and operative connection between the slotted plate and louver strips, substantially as and for the purpose set forth.

80 8. Ventilating means, comprising a cham-

ber, a "hit and miss" grating including a slide at the rear of said chamber, a series of louvers mounted in the entrance of said chamber in front of said grating and adapted to open or close said entrance, operative connection between the slide and louvers, vertical pivots for said louvers, a sliding bar connecting said louvers together, said bar having a forwardly extending arm 40 accessible from outside the carriage, whereby the movement of said bar to the right or left hand brings about simultaneously the opening or closing of the grating and the louvers, substantially as set forth.

45 9. Ventilating means, comprising a chamber, a "hit and miss" grating including a slide at the rear of said chamber, a series of louvers pivotally mounted in the entrance of said chamber, operative connection between said slide and louvers for insuring simultaneous operation thereof, and receptive means arranged beneath said chamber and adapted to discharge cinders and other solid particles which may strike the blank 50 portions of the grating and fall therefrom, substantially as set forth.

ALBERT ALFRED MEAD.
